REVOLVING DOOR

Edmund Peremi, Manhasset, and Charles Kish,
Elmhurst, N. Y., assignors to General Bronze
Corporation, Long Island City, N. Y., a corpo-
ration of New York

Application December 8, 1933, Serial No. 701,410

9 Claims. (Cl. 20—18)

This invention relates to revolving doors where-
in the several leaves are normally disposed in
radial positions for rotation in unison about a
common center, but are foldable into book form
5 to clear the doorway when desired.

It is an object of the invention to provide
improved means for guiding and controlling the
leaves in the folding movements thereof.

The present invention is related to the inven-
10 tions disclosed in the copending application of
Edmund Peremi and Charles Kish, filed Novem-
ber 7, 1933, Serial No. 696,953, now Patent No.
1,983,396, for Revolving doors, dated December
4, 1934, and the copending application of Edmund
15 Peremi and Charles Kish, filed November 18, 1933,
Serial No. 698,570, now Patent No. 1,983,395, for
Revolving doors, dated December 4, 1934.

In said Patent No. 1,983,396, provision is made
of means for guiding the leaves in their folding
20 movements, comprising a central gear of irreg-
ular form, a surrounding guide having internal
guiding surfaces, and on each leaf a pinion block
guided and confined by and between the external
guide and the central gear.

25 In one illustrative embodiment of the present
invention the principle of the invention of said
application is adhered to, but the central gear
is made regular in form, the pinion blocks are
formed with a series of like teeth or lobes for
30 engaging the central gear, and the pinion blocks
are further constructed so that the side teeth or
lobes may operate in overlapping relation and
may simultaneously engage a single seat or notch
of the central gear.

35 In another illustrative embodiment of the in-
vention the central support is provided with
upper and lower fixed discs, each disc having in
one face thereof a groove which is continuous
and generally square, but in which the ends of
40 the straight groove portions are connected
through arcuate portions. These arcuate por-
tions are concentric with guide pins provided
on the disc just inside the corners of the square
grooves, and also with divergent guide grooves
45 which intersect the straight portions of the
square groove and form branches of an inner
radial portion. Each leaf is provided with a pair
of guiding elements for cooperating with the
guide grooves and pins of the disc.

50 In both illustrative forms of the invention
adjacent leaves are adapted to make common use
of certain of the guiding elements of the disc,
and all of the guiding elements of the disc are
provided at one side of the disc. The upper disc
55 therefore may be mounted to present to view a

substantially smooth lower surface and the lower
disc may be mounted to present to view a sub-
stantially smooth upper surface.

Other objects and advantages will hereinafter
appear. 5

In the drawings forming part of this specifi-
cation:

Figure 1 is a view in sectional elevation of a
doorway having a door mounted therein which
embodies features of the present invention; 10

Figure 2 is a sectional, plan view illustrating
the structure of Figure 1 together with a dotted
line showing of the door folded into book form
and moved to one side of the doorway;

Figure 3 is a fragmentary, sectional view in 15
elevation through the lower central portion of the
door of Figure 1;

Figure 4 is a fragmentary, horizontal, sectional
view illustrating the construction of the leaf con-
trolling means; 20

Figure 5 is a view generally similar to Figure
4, but showing the leaves folded into book form;

Figure 6 is a fragmentary sectional plan view
illustrating another embodiment of the invention
with the leaves folded into book form; 25

Figure 7 is a fragmentary view in sectional eleva-
tion illustrating particularly the groove and pin
arrangement of the embodiment of Figure 6;

Figure 8 is a fragmentary detail view in sec-
tional elevation illustrating the disc construction, 30
the section being taken on the line 8—8 of Figure
9 looking in the direction of the arrows; and

Figure 9 is a fragmentary plan view illustrat-
ing the leaves in their normal radial positions.

Disclosure is made in Figure 1 of the customary 35
doorway comprising a floor 1, a ceiling wall 2,
and arcuate side guides 3. The door 4 is mounted
upon a central shaft 5 which extends upward
through the ceiling wall and which is suspended
from a trolley (not shown). The trolley is mount- 40
ed on tracks (not shown) and may be moved to
one side of the doorway when the door leaves
are folded into book form, as illustrated in dotted
lines in Figure 2.

For the purposes of supporting and guiding the 45
leaves from the central shaft, provision is made of
upper and lower control discs 6, the hub portions
of which are fixed to the shaft 5. Above, below
and between the discs provision is made of sleeves
7 having grooved faces 8 into which the inner 50
faces of the leaves fit when the leaves are in
their normal radial positions.

Each guide disc 6 comprises an inner flange 9
in the form of a gear having teeth 10 provided at
uniform intervals upon the periphery thereof and 55

arcuate grooves 11 intervening between each pair of successive teeth. The teeth 10 are all alike and the grooves 11 are all alike. A pinion block 12 is fixedly mounted on each leaf for cooperation with the gear formed by the inner flange. The pinion block is confined and held in engagement with the gear by an outer guide flange 13 of the disc 6. The pinion blocks are duplicates of one another. In folding the door into book form the pinion blocks (all located at the same side of the disc) are required to operate in overlapping relation, and hence clearance is provided to enable them to operate in such relation without conflict. To this end the upper halves of alternate pinion blocks are partially cut away to provide clearance, and the lower halves of the other blocks are partially cut away to provide clearance. While the blocks are duplicates of one another, therefore, adjacent blocks stand in inverted relation to one another.

Each pinion block comprises three like lobes or teeth 14, 15 and 16. The lobe 15 normally occupies and fits a notch or groove 11a of the central gear and is held thereto by engagement of an outer arcuate surface 17 of the pinion block with a similar arcuate surface 18 of the guide flange 13. The surface 18 is concentric with the face of the groove 11a and the surface of the lobe 15 is concentric with the surface 17 of the pinion block. When a leaf 4a is to be swung toward the right from normal position, the lobe 15 turns against the surface of the groove 11a and the surface 17 travels along the surface 18 until the lobe 16 becomes seated in the next groove or recess 11b of the central gear. At this instant the surface 18 clears the surface 17. In the continued folding movement of the leaf the lobe 14 is held to the seat provided by the groove 11b by the interengagement of arcuate surfaces 19 and 20 provided on the pinion block and the outer guide flange 13, respectively. The right and left hand halves of the pinion block are duplicates of one another.

When a leaf 4b is to be swung toward the left, the pinion block 12 thereof is controlled by the inner flange 9 and the outer guide flange 13 in the manner already described. In this movement a lobe of the pinion block of leaf 4b enters and becomes seated against the base of groove 11b. These overlapping lobes are accordingly provided in different planes by removing the upper half of one lobe and the lower half of the other. The same practice is carried out to provide clearance for overlapping of side portions of the pinion blocks with one another, the overlapping being indicated between the several pairs of adjacent pinion blocks in Figure 5. The construction is such that each pinion block comprises side pieces 21 confined to one half of the thickness of the block, a central boss 22 occupying the full height of the block and having a tongue portion 23 extending centrally to the outer extremity of the block, and an inner lobe 15 extending throughout the height of the block. The leaves 4c, 4b, 4a and 4d may be folded into book form, as illustrated in Figure 5.

Provision is made of means for detaining the leaves normally in their radial positions, such detaining means being generally like the detaining means disclosed and claimed in Patents Nos. 1,983,396 and 1,983,395, hereinbefore referred to.

The detaining mechanism is designed to yield in response to force intentionally exerted by an operator when it is desired to clear the doorway for the reception or delivery of merchandise or

for any other purpose, and also in case of panic by persons rushing heedlessly against the leaves. The detaining means comprises in each instance a pair of oppositely flexed toggles comprising links 24 and 25 which normally engage in notches 26 and 27 formed in the outer face of the flange 13. The toggles are alternatively effective, one requiring to be straightened in order to fold the leaf in one direction, and the other requiring to be straightened in order to fold the leaf in the opposite direction. Straightening of the toggles is resisted by a spring 32 mounted in the door leaf. Each of the toggle arms is pivotally connected at the outer end thereof to a slide block 33, such slide block forming the second element 15 of each of the toggles, the slide block 33 has a beveled upper face 34 at the outer end thereof which engages a beveled face 35 formed upon the inner end of a lever 36. The lever 36 is mounted upon a fulcrum pin 37 and rests at its outer end upon a plunger 38. The plunger 38 has a stem portion which is slidably vertically in a bore 39 formed in a carrier 40. The spring 32 is seated in an annular recess 41 formed in the carrier 40. The spring 32 encircles the plunger and bears against the lower side of the head thereof to hold the plunger constantly in engagement with the outer arm of the lever 36. The lever 36 is held by the plunger in engagement with a fixed stop 42 provided on an upper housing member 43. A 30 rack bar 44 is secured upon the carrier 40 by means of screws 45 and meshes with a pinion 46 fast on a shaft 47. The shaft 47 has a square opening 48 in the end thereof which is accessible from the exterior of the door leaf and which is 35 adapted to be operated by the insertion of a key to slide the plunger 38 toward and from the fulcrum of the lever 36. The inner end of the carrier 40 is obstructed by a shoulder 49 formed on lower housing member 50 so that the plunger 40 cannot be carried to a position directly beneath the fulcrum of the lever 36. In this respect the present construction differs from the disclosures of Patent No. 1,983,396 and Patent No. 1,983,395. Since it is not possible to take the spring 32 completely out of action, the provision of a light auxiliary spring for urging the slide block 33 inward is unnecessary. An adjustable stop bar 51 is attached by screws 52 to the carrier 40 as in Patent No. 1,983,395 for selectively determining an outer 50 limit of movement of the carrier and hence the maximum effectiveness of the spring 32 upon the lever 36. The stop bar 51 cooperates with a fixed stop 52a on the housing member 50. The detent mechanism as shown and described is claimed in 55 Patents Nos. 1,983,396 and 1,983,395 with the exception that no claim is made in said applications to the feature of limiting the effectiveness of the spring 32 to a predetermined minimum value.

Each leaf is adapted to be folded upon occasion 60 through as much as 135° in either direction away from the normal radial position thereof.

For the purpose of aiding in determining positions of the leaves removed 45° and 135° from normal, provision is made on each leaf of a well 65 28 containing a plunger 29, a spring 30 acting on the plunger, and a threaded plug 31 for holding the spring against the plunger. Each plunger extends into contact with the smooth face of a disc 6, and the disc is provided with sixteen depressions, four for each plunger, to define two positions of each leaf 45° removed from normal, and two positions 135° removed from normal.

In the embodiment of Figures 6 to 9 the general construction of the door is the same as that 75

in the embodiment of Figures 1 to 5. That is to say, a central rotary shaft 5a suspended from a trolley is provided with fixed upper and lower discs 6a, and four leaves normally held in radial 5 positions are mounted upon the discs with provision for swinging movement in either direction for as much as 135° away from normal. Each disc comprises a square groove 53 having straight sides 54 and round corners 55. Each disc is also 10 provided with a guide pin 56 within each corner, and concentric with the round groove portion at such corner. Each disc is further provided with a radial groove 57 having divergent arcuate portions 58 and 59, one arcuate portion 58 being concentric with the guide pin 56 located near one corner of the square groove and the other arcuate portion 59 being concentric with the guide pin 56 located near an adjacent corner of the square groove. The middle of each side portion 54 of 15 the square groove intersects the junction of the grooves 58 and 59. The square groove is deeper than the groove 57 and the branches thereof.

Each door leaf carries a fixed pin 60 which normally fits in the groove 57 at the inner end thereof, and which is adapted to fit the grooves 51, 58 and 59. Each leaf also carries a fixed pin 61 upon which is mounted a roller 62. The roller 62 fits the square groove 53 and extends for substantially the full depth thereof. The pin 60, cooperating with the grooves 57 and 58 or 59 together with the roller 62 cooperating with the groove 54, is fully capable of guiding and controlling a leaf throughout its entire swinging movement of 135°, with the exception that the pin 60 is without 20 support at one side at the point in its travel where it nears and crosses the junction of grooves 58 and 59. The guide pins 56 are provided for assisting in controlling the leaves during such periods of their movements. Each leaf is provided at 25 opposite sides thereof with projections 63 having guide notches 64 formed therein. The notches 64 have arcuate surfaces provided at the bases thereof which are adapted to fit and slide upon the pins 56.

When leaf 65 is swung clockwise from its normal position illustrated in Figure 9, the pin 60 carried by the leaf travels outward in the radial groove 57 and the roller 62 travels toward the right along the straight portion 54 of the square groove 53. The condition of the parts occurring at the time when the leaf is swung 45° away from normal is illustrated in Figure 6 with reference to the leaf indicated in the position 65a. It will be observed that the pin 60 and the roller 62 still occupy straight portions of the grooves with which they cooperate. In the further swinging movement toward a condition like that of the leaf illustrated at 65b in Figure 6, the base of the notch 64 is carried into engagement with a guide pin 56. The roller 62 simultaneously reaches an arcuate corner portion 55 of the square groove 53 and, at the same time, the pin 60 reaches a widened portion of the groove 57. The pin 56 and the notch 64, however, cooperate with the 30 roller 62 to control the door during the transitional period when the pin 60 is passing over from the radial groove portion 57 to the arcuate groove portion 59. The pin 60 moreover is traveling constantly in engagement with the surface of the grooves 57 and 59 at the inner side of the curve, except at the time when the pin is actually crossing the groove 53.

The cooperation of the leaf guiding elements 35 when the leaves are swung counterclockwise is the

same as that already described for the clockwise movement. In Figure 6 the leaf illustrated in the position marked 65c has been swung 45° away from normal in a counterclockwise direction and the leaf marked 65d has been swung 135° away from normal in a counterclockwise direction. It will be observed that the same guide pins 56 and the same arcuate groove portions 55 are utilized for controlling the swinging movement of one leaf in a clockwise direction and for controlling the swinging movement of an adjacent leaf in a counterclockwise direction.

The detent mechanism employed in the embodiment of Figures 6 to 9 may be the same as that already described as employed in the embodiment of Figures 1 to 5. Plunger detents 66 are also provided on each leaf for cooperating with notches 67 formed in the smooth faces of the discs for determining 45° and 135° positions of the leaves.

While we have illustrated and described in detail certain preferred forms of our invention, it is to be understood that changes may be made therein and the invention embodied in other structures. We do not, therefore, desire to limit ourselves to the specific construction illustrated, but intend to cover our invention broadly in whatever form its principle may be utilized.

We claim:

1. In a revolving door, in combination, a central rotary support, leaves foldably mounted on the support, and means for controlling and guiding the leaves in their folding movements comprising a guide disc fixed on the support and having a central gear flange provided with a series 30 of equally spaced arcuate notches all equidistant from the axis of the support, a pinion block fixed on each leaf and each including a plurality of lobes for cooperating with the gear notches, said guide disc also having an outer flange having 35 successive inner guiding surfaces concentric with the successive notches for guiding and confining the pinion blocks in their movements.

2. In a revolving door, in combination, a central rotary support, leaves foldably mounted on 45 the support, and means for controlling and guiding the leaves in their folding movements comprising members carried by the leaves and the central support respectively, said central-support-carried means comprising a central circular 50 gear having a series of equally spaced arcuate notches formed in the periphery thereof, a surrounding guide having guiding surfaces concentric with the gear notches and the leaf carried 55 means comprising a pinion block on each leaf having concentrically arranged lobes for cooperating with the central gear, each block being continuously confined and guided by the central gear and the surrounding guide.

3. In a revolving door, in combination, a central rotary support, leaves foldably mounted on the support, and means for controlling and guiding the leaves in their folding movements, comprising members carried by the leaves and the central support, respectively, said central-support-carried means comprising a central circular 60 gear having a series of equally spaced arcuate notches formed in the periphery thereof, a surrounding guide having guiding surfaces concentric with the gear notches and the leaf carried 65 means comprising a pinion block on each leaf having concentrically arranged lobes for cooperating with the central gear, each block being continuously confined and guided by the central 70 gear.

75

- gear and the surrounding guide, certain of the gear notches being located for cooperation with the lobes of the pinion blocks of adjacent leaves and said lobes being of less height than the pinion blocks and located in different planes so that they may operate in overlapping relation.
4. In a revolving door, in combination, a central rotary support, leaves foldably mounted on the support, and means for controlling and guiding the leaves in their folding movements comprising a circular central gear fixed on the central support and pinion blocks individual to the leaves and having lobes cooperative with the gear, said pinion blocks having marginal portions thereof cut away to limit the remainder of such marginal portions to heights not substantially exceeding one-half the height of a block, and the pinion blocks of adjacent leaves being disposed in inverted relation to one another to enable them to operate in overlapping relation.
5. In a revolving door, in combination, a central rotary support, leaves foldably mounted on the support, and detent means individual to the leaves for retaining the leaves yieldingly in normal radial positions comprising in each instance a pair of normally flexed alternatively effective toggles, a spring for applying force to the toggles, force transmitting means interposed between the spring and the toggles, a spring carrier operable to alter the effectiveness of the spring, while maintaining the stress thereof substantially unchanged, and means limiting the movement of said carrier in a direction to diminish the effectiveness of the spring whereby a reduction of the effectiveness of the spring below predetermined minimum value is prevented.
6. In a revolving door, in combination, a central rotary support, leaves foldably mounted on the support, and detent means individual to the leaves for retaining the leaves yieldingly in normal radial positions comprising in each instance a pair of normally flexed alternatively effective toggles, a spring for applying force to the toggles, force transmitting means interposed between the spring and the toggle, a spring carrier operable to alter the effectiveness of the spring, while maintaining the stress thereof substantially unchanged, and means limiting the movement of

said carrier in a direction to diminish the effectiveness of the spring, said means being fixed and unalterable, whereby a reduction of the effectiveness of the spring below a predetermined minimum value is positively precluded.

7. In a revolving door, in combination, a central rotary support, leaves foldably mounted on the support, a detent carried by each leaf, a spring acting on each detent to make it effective, a spring carrier movable to alter the effectiveness 10 of the spring, and means limiting the movement of said carrier in a direction to diminish the effectiveness of the spring, said means being fixed and unalterable whereby reduction of the effectiveness of the spring below a predetermined 15 minimum value is positively precluded.

8. In a revolving door, in combination, a central rotary support, leaves foldably mounted on the support, and means supporting and guiding the leaves in their folding movements, comprising 20 a disc on the central support having a square groove with rounded corners, guide grooves concentric with the rounded corners of the square groove and guide pins also concentric with the rounded corners of the square groove and guiding 25 elements on each leaf cooperative with said grooves and pins.

9. In a revolving door, in combination, a central rotary support, leaves foldably mounted on the support, and means supporting and guiding 30 the leaves in their folding movements comprising a disc on the central support having a square groove with rounded corners and radial grooves extending transversely of the sides of the square groove at the middle portions thereof and having 35 arcuate branches concentric with the rounded corners and intersecting the square groove, guiding abutments on the disc concentric with the rounded corners of the square groove and guiding elements on each leaf cooperative 40 with the grooves and abutments, the abutments and rounded corners of the square grooves being arranged to support the leaf when the leaf element, cooperative with the radial groove and its branches, is crossing the square groove. 45

EDMUND PEREMI.
CHARLES KISH.
